UNITED STATES PATENT OFFICE.

WILLIAM S. AUSHERMAN, OF TALMAGE, KANSAS.

AUTOMATIC LIQUID PUMP.

Application filed June 1, 1923. Serial No. 642,846.

To all whom it may concern:

Be it known that I, WILLIAM S. AUSHERMAN, a citizen of the United States, residing at Talmage, in the county of Dickinson and State of Kansas, have invented a new and useful Automatic Liquid Pump, of which the following is a specification.

This invention aims to provide a simple coin-control for a dispensing pump of the sort used in handling gasoline and other liquids. The invention aims, further, to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

It is within the province of the disclosure to improve generally and to enhance the utility of devices of that type to which the invention appertains.

In the accompanying drawings:—

Figure 1 shows in vertical section, a device constructed in accordance with the invention, parts appearing in elevation; Figure 2 is a section on the line 2—2 of Figure 1, parts appearing in elevation; Figure 3 is a section on the line 3—3 of Figure 1.

In carrying out the invention, there is provided a support or casing 1 supplied at its upper end with a guide 2 and equipped at its lower end with a gland 3. The liquid to be disposed is pumped upwardly through a pipe 4 having a laterally extended spout 5, the pipe being connected to the lower portion of the casing 1 if desired. In the upper part of the casing 1 there is a coin chute 6.

A coin placed in the chute 6 ultimately finds its way into a drawer 7 slidably mounted in the lower portion of the casing 1. At its lower end, the coin chute 6 has a substantially vertical mouth 8.

A shaft 9 is journaled for rotation in the casing 1 and may be rotated through the instrumentality of a crank 10 or otherwise. A ratchet wheel 11 is secured to the shaft 9 and is located within the casing 1. The ratchet wheel 11 is engaged by a back stop pawl 12 pivotally mounted at 14 on the cas-

ing 1. The ratchet wheel 11 has a radial slot 15 wherein a wrist pin 16 is adjustably mounted, thereby to vary the throw of a pump plunger 17 mounted for reciprocation in the guide 2 and in the gland 3, and constituting part of the mechanism whereby the liquid to be dispensed is carried upwardly through the pipe 4 and outwardly through the spout 5. The lower end of a pitman is mounted pivotally on the wrist pin 16 and the upper end of the pitman is pivoted at 19 to the pump plunger 17.

On its periphery the ratchet wheel 11 is supplied with a projection 20 located to one side of the teeth of the ratchet wheel. The projection 20 is adapted to cooperate with a detent or lever 21, mounted to move between stop pins 33 on the casing 1 and fulcrumed intermediate its ends, as at 22, on a bracket 23 carried by the casing 1. A hanger 25 is pivoted at 24 to the outer end of the detent 21.

A coin receptacle is provided, and is denoted generally by the numeral 26. The coin receptacle 26 comprises oppositely disposed trough-shaped members 27, one of which fits slidably within the other, one of said members having an elongated edge-opening for the reception of the lower end of the coin chute 6. At their upper ends, the members 27 of the coin receptacle are pivoted as at 28 to the hanger 25. One member of the coin receptacle has a vertically elongated guide 29 mounted to slide on a bracket 30 which is carried by the casing 1. A retractile spring 31 is connected at its ends to the members 27 of the receptacle, to draw the lower ends of said members together. The inner walls of the members 27 of the coin receptacle 26 have inwardly extended converging cams 35.

In practical operation, a coin is inserted into the coin chute 6 and moves downwardly into the coin receptacle 26. Under the weight of the coin in the coin receptacle, the detent lever 21 is tilted on its fulcrum 22 and, thus, the inner end of the detent lever is moved out of the path of the projection 20 on the ratchet wheel 11. This operation sets the ratchet wheel free for rotation, and the ratchet wheel may be turned through the instrumentality of the shaft 9 and the crank 10. When the ratchet wheel 11 is rotated, the pitman 18 imparts reciprocation to the pump plunger 17, and a quantity of other liquid is forced through the pipe 4 and out

of the spout 5. When the ratchet wheel 11 is rotated, the projection 20 rides between the cams 35 on the members 27 of the coin receptacle 26 and spreads them apart, permitting the coin to drop from the coin receptacle 26 into the drawer 7. As soon as the projection 20 on the ratchet wheel 11 is free from the cams 35, the members 27, of the coin receptacle 26 swing back into the closed position shown in Figure 3 of the drawings, under the action of the spring 31. As soon as the coin receptacle 26 is relieved of the weight of the coin, the detent lever 21 drops back into the position shown in Figure 1 in contact with the lowermost stop pin 33, the inner end of the detent lever being disposed in the path of the projection 20 on the ratchet wheel 11. When the ratchet wheel 11 has been rotated sufficiently, the projection 20 comes into contact with the inner end of the detent lever 21, and, thus, the action of the pump mechanism is stopped, it being impossible for the purchaser to secure a greater quantity of liquid than that called for by the depositing of a single coin. It is to be observed that the projection 20 exercises a two-fold office. First, cooperating with the detent lever 21, it constitutes a means for stopping the rotation of the ratchet wheel 11, and, secondly, entering between the cams 35 of the coin receptacle 26, it constitutes a means for swinging the members 27 of the receptacle apart, on their pivotal mounting 28, thereby permitting the coin to drop from the coin receptacle into the drawer 7.

What is claimed is:

1. In a device of the class described a coin receptacle comprising separable parts, a movable detent carrying the receptacle, a rotary member including a projection engaging the detent to hold the rotary member against rotation, the detent being movable out of engagement with the projection under the weight of a coin in the receptacle, and the projection being so located as to separate the parts of the receptacle and to permit a discharge of the coin in the receptacle and to permit a return of the detent into engagement with the projection.

2. In a device of the class described, a coin receptacle comprising separable parts, a detent lever, means for fulcruming the lever intermediate its ends, means for mounting the parts of the receptacle pivotally on the lever, a rotary member, and a projection on the rotary member, the projection cooperating with the detent lever to hold the rotary member against rotation, the projection being adapted to coact with said parts of the coin receptacle to bring about a separation thereof and a discharge of the coin, thereby permitting the detent lever to return into the path of the projection.

In testimony that I claim the foregoing as my own, I have hereto affixed my signature in the presence of two witnesses.

WILLIAM S. AUSHERMAN.
